UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

FLUID COMPRESSOR AND METHOD OF COOLING THE SAME.

Application filed September 15, 1924. Serial No. 737,725.

My invention relates to fluid compressors of the sleeve valve and cylinder type, such as disclosed in the French patent to Renault, and provides an improvement in structure and method of cooling.

Where a compressor is to be operated continuously in compressing a fluid to terminal pressures of three atmospheres or more, means must be provided for preventing excessive temperatures incidental to the compression of the fluid other than the mere radiation of the heat from the cylinder head and walls.

The heat which is generated in compressing the fluid is conducted to the cylinder head, the piston head, and to the walls, and it must be moved through the head and walls to the outside if the temperature is to be controlled. The heat that may be transmitted by conduction to the walls through the end and side walls of the compression chamber depends chiefly on three factors, namely, the radiating or conducting character of the outer surface of these walls, the thickness of the walls themselves, and the difference in temperature between the inside and the outside of the compression chamber. The last factor is perhaps best capable of control and, hence, is the greatest contributing factor to securing low, final or terminal discharge temperature. In the design of single stage fluid compressors for continuous duty at final discharge pressures of three atmospheres or more, it is considered the best practice at present to surround the compression chamber as nearly as possible by a jacket through which water is passed. This establishes generally a high difference of temperature between the inside and outside walls and tends to promote the efficiency of the compressor.

Water jacketing is not entirely satisfactory since it is not possible to completely surround the compression chamber by the water jacket, as the compressor piston of a single acting compressor forms one end of the chamber which cannot be practically water-cooled without danger to the lubrication and excessive complication in construction. The cylinder head with its valves can be water-cooled only partially, as the space which suction and discharge pockets occupy in many compressors cannot be satisfactorily cooled.

rily cooled. Furthermore, they comprise the major portion of the active area of the compressor head. It is at the head and top of the cylinder wall that the highest temperatures will be reached during compression, and since this area cannot be reached by water-cooling in a satisfactory degree, it will be seen at once that these parts are subject to excessive temperatures even when other parts are fairly cool.

The cylinder walls may be satisfactorily cooled but they do not have a great influence upon the terminal pressures. The cooling of the side walls of the compression chamber is useful in maintaining a better lubrication of the piston and, hence, is highly useful. It does not, however, appreciably promote the volumetric efficiency nor the ability to operate continuously, so far as temperature rise is concerned, as it maintains only the mechanical lubrication.

Another difficulty with compressors of the conventional type is that the clearance at the discharge end of the compressing chamber in both the compression chamber and in the valve pockets, contains heated fluid at the end of the compression stroke which, together with the slippage of the discharge valve, allows the heated air to expand back into the compression chamber as the piston starts the suction stroke. This fluid being at the terminal temperature, raises the general temperature of the fluid which is introduced into the compression chamber by the suction stroke and, hence, there is a constant building up of temperature due to inability to scavenge the cylinder at the end of the discharge stroke.

According to my invention, I scavenge the clearance space immediately upon the completion of the compression stroke, displacing the heated air or other fluid with free air or other fluid and thereby ridding the compressor of the heat which was contained in fluid in the clearance space.

While I have embodied my invention as disclosed in the present drawings and specification in an air compressor, it is to be understood that the invention may be employed in compressing other compressible fluid, and herein where I speak of an air compressor or air, I refer generally to a fluid compressor or fluid.

In the case of water-cooled compressors, it is to be noted that they are not generally applicable, because cooling water may not be available or the difficulty of providing cooling water in winter may be prohibitive. In such case the prior art has been compelled to install a compressor which would be of much more expensive construction as, for example, by intermittent stages of operation or multi-stage compression or the like.

According to the present invention, I provide a method of cooling which will be applicable for cooling a compressor by the use of a current of free fluid which is being compressed that will permit of high rotative speeds under continuous operation without exceeding permissible temperatures.

My compressor and cooling system provides a structure which is self-contained, that is, the cooling system is made a part of the compressing unit, and it does not depend upon an external source of cooling fluid. Furthermore, since I use the same fluid which is being compressed, freezing temperatures are not detrimental. The unit is light in weight and simple and inexpensive to manufacture.

In order to acquaint those skilled in the art with the manner of constructing and operating a device embodying my invention, I shall now disclose in connection with the accompanying drawings a specific air compressor embodying my invention.

In the drawings,
35 Fig. 1 is a vertical central cross section;
Fig. 2 is a side view showing a part of the compressor in section;

40 Fig. 3 is a vertical section similar to that shown in Fig. 1 of the upper end of the cylinder and the head showing the piston on its downward stroke;

Figs. 4 and 5 are cross sections taken on the lines 4—4 and 5—5, respectively, on Fig. 3.

45 In the embodiment shown in the drawings, the compressor 1 and its driving motor 2 are mounted upon a common base 3 with a flexible coupling 4 connected between the motor shaft 5 and the fly wheel 6. The fly wheel 6 is provided with bosses or lugs 7 to which are clamped the flexible discs 8, these discs being in turn connected to the motor shaft through spider arms 9. The fly wheel 6 is keyed or otherwise secured to the end of 50 the crank shaft 10, this crank shaft having bearings 11 and 12 supported in the side walls of the crank case 13. The crank case 13 is preferably provided with drip cups 14 communicating with the bottom of the crank case 13 and surrounding the lower part of the crank shaft 10. The crank case 13 is preferably made in two sections, that is, split upon the line of the crank shaft bearings 11 and 12. The crank case 13 has an 55 extension 15 for mounting the compressor

upon the base 3, this extension 15 being suitable in height to bring the crank shaft of the compressor in line with the motor shaft and also providing sufficient clearance for the fly wheel 6. The upper section of the 70 crank case 13 merges into a cylinder housing 16 having a cylindrical bearing ring 17 at its lower end and providing also a similar bearing ring 18 at an intermediate point adjacent the upper end. The cylinder housing 16 which may be termed "the cylinder" 75 contains a suitable sleeve or liner 19 having cylindrical bearing surfaces cooperating with said bearing surfaces 17 and 18, as indicated at 20 and 21. As the piston has its bearing inside of the liner 19 and the actual work of compressing the fluid is carried on inside of this liner, I may term the liner herein the "working cylinder," since functionally that is its duty. This is to distinguish it from that part of the structure, namely, the cylinder 16, the function of which is to support the liner or working cylinder and the cylinder head. This liner or working cylinder in addition to its function of operating in conjunction with the piston as the working cylinder also functionally serves as a sleeve valve operated by ring friction. The remaining outside surfaces of the sleeve or liner 19 may be corrugated, as indicated at 22 and 23, for greater efficiency in cooling. The cylinder housing 16 has a cylinder head 24 secured as by means of the cap screws 25 to the top thereof. This head 80 contains a suitable seating ring 26 in position to engage with the inturned flange 28 of the upper end of the sleeve or liner 19 to make a fluid tight joint. The ring 26 surrounds the discharge opening 27 which has a valve seat 29 adapted to be closed by the discharge check valve 30 which, in this case, has a hollow stem or sleeve 31 guided upon the hollow post or stud 32 forming a part of the discharge connection 33 which is provided with a threaded seat or socket 34 to receive the discharge pipe. The check valve 30 is held to its seat by a coiled spring 35 seated in the hollow stud 32. A discharge chamber 36 is formed about the valve and its guide by a shell or cylindrical housing 37. 85 This shell or cylindrical housing is formed integral with the cylinder head at its lower end, and at its upper end is threaded to receive the fitting 33. 90 The shell or housing 37 is joined to the cylinder head by a relatively narrow neck. This is of importance because it limits the contact of the hot compressed air with the top of the cylinder head. It will be noted that the use of this narrow neck permits the top of the cylinder head above the yielding seat 26 to be cooled constantly and it limits the conduction of heat from the compressed air in the pocket 36 to the said yielding seat 26. Since this seat is made of yielding ma- 95 100 105 110 115 120 125 130

terial, it is important that it be kept relatively cool or it will quickly deteriorate.

While the above is the construction preferred for embodying the invention in a simple single stage compressor, it is to be understood that the discharge valve construction may be widely varied within the limits of my invention.

The discharge chamber 39 is surrounded by a conduit or wind chest 38 which has openings, as indicated at 39, for discharging air against the top of the cylinder head 24 preferably at a point closely adjacent the discharge valve seat. This wind chest 38 is connected by a conduit or tunnel 40 which is formed integral therewith and which is fastened as by means of the flanges 41 to the side wall of the cylinder housing, a boss 42 being formed at that point. Diametrically opposite the boss 42 there is formed a similar boss for air admission. To the boss 43 I have connected the flanged end of the blower discharge pipe 44, this pipe being formed integral with the housing 45 of a suitable blower or fan 46. A wind box or conduit is formed about the upper end of the liner or sleeve 19, as indicated at 47, in order to permit the air delivered by the fan or blower 46 to surround completely the upper end of the sleeve or liner 19.

Preferably, but not necessarily, restricting baffles 48 are arranged in the discharge ends of the passageways or chambers 47. This is for the purpose of restricting the flow of air while the sleeve or liner 19 is in raised position and the working cylinder therefore closed, in order to build up a slight pressure from the fan 46 for more readily and quickly scavenging and cooling the cylinder, cylinder head and piston when the cylinder is opened.

45 A duct or passageway 50 leads to the space 51 between the cylinder housing 16 and the liner 19, and a discharge opening 52 permits the air which passes down to cool the lower end of the cylinder liner to escape at this point. Other means for providing cooling fluid for the lower part of the liner 19 may be provided without departing from 50 the spirit of my invention.

The cylinder liner 19 at the enlargement 21 has a projecting ring or annular shoulder 53, which is adapted to contact with a yielding ring 54 for stopping the downward motion of the liner 19 to silence the operation of the device.

The compressor piston 55 has suitable rings, as is well understood by those skilled in the art, for maintaining a fluid tight fit between the piston and the walls of the compression chamber, in this case the liner 19. The piston 55 is connected to a suitable connecting rod 56 of any preferred or usual construction to the crank pin 57 on the crank shaft 10.

In the device illustrated, the fan or blower 46 is driven by means of a grooved pulley 58 on the blower shaft, the outer end of the shaft being supported upon a bracket 59 mounted on the side walls of the cylinder housing 16. A round belt 60 is trained over the pulley 58 and the fly wheel 6, a suitable groove 61 being formed on the periphery of the fly wheel 6 next to the compressor.

The particular blower 46 which I have 75
illustrated is illustrative of any suitable de-
vice for creating a current of air in excess
of the amount required by the downward
motion of the piston 55 when the compressor
is operating at its rated speed. That is to 80
say, any suitable device for supplying a flow
of free air, preferably at a slight pressure
above atmosphere, may be provided instead
of the particular fan shown at 46. The fly
wheel 6 may be formed with vanes for cre- 85
ating a blast of air which will serve the
purpose.

The operation of the device is as follows:—

The cylinder liner 19 which forms the side walls and a part of the end walls of the compression chamber, is adapted to be moved up and down with the piston 53 by the ring friction; that is, the friction between the piston and the liner created by the piston rings. The liner 19 is permitted to move only a very short distance until the flange or ring 53 strikes the yielding

stop or seat 54 in the downward direction. This is shown in Fig. 3. The blower 46 which has been delivering air through the pipe 44 and the passageways or box 47 about the top of the liner, now blows air through the opening between the top of the liner and the bottom of the cylinder head, thereby sweeping out the heated air which remains in the clearance space and, at the same time, cooling off by contact the top of the piston 55 and the bottom surface of the head 24, the valve 30, and the yielding seat 26. The yielding seat 26 is permissible because the temperature is kept relatively low and it has the advantage of quieting the operation of the device very materially and securing a better fit than could be secured by a plain flat metal to metal seat. The

by a plain flat metal-to-metal contact. The air which is blown in by the blower 46 is considerably in excess of the maximum intake requirements of the retreating piston 55. In the form illustrated, I have provided for an excess flow of air at least 25 per cent greater than the air inflow to the compression chamber during the maximum speed of compressor piston movement in its downward stroke. Thus, at the early part of the stroke, substantially the entire delivery of air from the blower 46 goes to scavenge the clearance space and to cool off the cylinder and piston heads. By this action not only is the heated air which re- 130

mains in the clearance space scavenged, but the continuing blast of air sweeps over the heated surfaces cooling the same. The air after it cools the top of the liner, the bottom of the cylinder head and the top of the piston, is driven on through the conduit 40 into the wind box 38 and there through the nozzle 39 is discharged against the cylinder head and the receiving chamber about the discharge check valve 31. Upon the piston 55 reaching the bottom of the stroke, the motion thereof is reversed and at this time the ring friction seizes the liner 19 and the liner and the piston move up until the flange 28 on the liner strikes the yielding seat 26, closing the compression chamber, and the remainder of the stroke of the piston 55 compresses the fluid and drives it out through the delivery port 27 past the check valve 30. During this time, the top of the liner and the adjacent parts of the cylinder head are being cooled, and the blast from the nozzle 38 is effective in cooling the receiving or delivery chamber 36. The vibrating motion of the liner 19 need be only very light to secure a relatively large opening into the interior of the cylinder.

The purpose of the inturned flange at the top of the liner, indicated at 28, is to insure seating with internal pressure. This flange need be only great enough to insure that the cylinder will be maintained closed during the compression stroke, and should not be so great that ring friction will not readily open the cylinder when the piston begins to move downwardly.

While I have described an air compressor operating in atmospheric air at usual temperatures, it is to be understood that the compressor may be used to compress gas without departing from the spirit of the invention by enclosing the same in such a manner as to employ the medium which is compressed as a cooling medium.

It will be understood also, that instead of using a blower to force the air through as above described, an exhauster may be used at the opposite end to permit atmospheric pressure to drive the air through the passageway. The exhauster, however, has the disadvantage of lowering the efficiency of the compressor by reducing the pressure of the air in the cylinder at the beginning of the compression stroke.

The cooling air may be conducted through a suitable conduit from any desired point and may be filtered if desired.

I do not intend to be limited to the detail shown or described.

I claim:—

1. The method of cooling the piston and working cylinder of an air compressor which comprises opening the cylinder at the beginning of the suction stroke and blow-

ing free air into the working cylinder in excess of the volume demanded by the displacement of the piston.

2. The method of cooling a fluid compressor having a working cylinder, a cylinder head and piston, which comprises separating the working cylinder from the head at the beginning of the suction stroke of the piston and blowing free fluid across the bottom of the cylinder head and across the piston head. 70

3. The method of cooling a fluid compressor which comprises creating a current of free fluid into and out of the working cylinder during the suction stroke. 80

4. The method of cooling a fluid compressor which comprises creating a flow of free fluid through the working cylinder in excess of the volume required by piston displacement. 85

5. The method of cooling a fluid compressor and increasing its efficiency which consists in scavenging the working cylinder by a blast of free fluid. 90

6. The method of cooling a fluid compressor which comprises blowing more fluid into the working cylinder than it will hold during the suction stroke. 95

7. The method of cooling an air compressor which comprises blowing air completely across the bottom of the cylinder head during each suction stroke. 100

8. The method of cooling a compressor which comprises blowing a blast of air across the bottom of the cylinder head and out of the working cylinder during the suction stroke. 105

9. The method of operating an air compressor which comprises forcing a current of air into the working cylinder and out of the same during the suction stroke. 110

10. In a compressor, a cylinder having a movable liner, a head adapted to be engaged by the liner upon the beginning of the compression stroke, a yielding stop carried by the cylinder, and means on the liner for engaging said stop upon movement of the liner away from the cylinder head. 115

11. In combination, a cylinder having a movable liner, a head having a yielding seat adapted to be engaged by said liner, a yielding stop, means on the liner for engaging said stop upon movement of the liner away from the head. 120

12. In combination, a cylinder having a cylinder head, a movable liner, a piston having rings engaging the liner, said liner being adapted to be moved by ring friction, and means for forcing a current of air through the opening between the liner and the head during the suction stroke of the engine. 125

13. In combination, a cylinder having a head, a liner, a piston for the liner, said liner being moved by friction with the pis- 130

- ton, and means for blowing a continuous blast of air upon the upper end of the liner where it engages the head.
14. In combination, a cylinder housing, a movable liner in the housing, said housing having a head, the liner being adapted to engage said head, a piston in the liner for moving the liner away from the head upon the beginning of the suction stroke and against the head at the beginning of the compression stroke, said housing forming a wind box about the upper end of the liner and a blower operated concurrently with the compressor connected to said wind box.
15. In combination, a cylinder housing containing a movable liner, said housing having a cylinder head adapted to be engaged by the liner upon the beginning of the compression stroke, said liner being moved away from the head at the beginning of the suction stroke, said housing comprising a wind box surrounding the top of the liner, and baffle means about the sides of the liner in said wind box.
16. In combination, a cylinder having a cylinder head and a liner adapted to contact therewith to form a closed working chamber, said liner being movable by ring friction away from said head and against said head, and means for creating a forced current of air completely across the bottom of the head when the liner is moved away from the head.
17. In combination, a cylinder housing having a movable liner, a head having a seat for the end of the liner, a wind box about the end of the liner and under said head, means for flowing air into said wind box, a discharge valve for the head, and means for discharging air from the wind box upon the top of the head for cooling said head adjacent the discharge valve.
18. In an air compressor, a sleeve valve and means for creating a current of air in contact with the sleeve valve operated concurrently with the compressor for cooling said sleeve valve.
19. In combination, a cylinder housing having a movable liner therein adapted to be moved by ring friction, a head adapted to be engaged by the liner, a wind box about the upper end of the liner, an intake for the wind box on one side of the housing, a blower having its discharge connected to said intake, a discharge connection for the wind box opposite to the intake, and means communicating with said discharge for directing the air therefrom upon the top of the cylinder head.
20. In combination, a cylinder having a movable sleeve, said sleeve having an in-turned flange, a head, a spring actuated discharge check valve on said head, a piston in the sleeve, and yieldable stationary stop means for limiting the motion of the sleeve in each direction, the yieldable stop means including a yieldable valve seat on the cylinder head adapted to be engaged by said in-turned flange.
21. In combination, a cylinder having a head, a movable liner, a discharge valve-pocket connected to the head by a relatively small diameter neck, and communicating with the cylinder by a central passage through the head, a valve for said passage, said head having an annular yielding seat adapted to be engaged by the liner and a piston in the liner for moving the liner to and from the yielding seat for each cycle of the compressor.
22. In a compressor, a cylinder frame having radial inlet ports, a movable cylinder sleeve mounted therein, a head mounted on the frame, a central discharge port, a check valve therefor, a yielding annular seat surrounding the discharge port and co-operating with the top of the movable cylinder sleeve, and a piston having rings fitting in the cylinder and adapted to move the plunger by ring friction.
23. In a compressor, a cylinder frame, a cylinder head mounted thereon, a movable sleeve cylinder in the frame, a discharge check valve chamber connected to the top of the head by a neck of relatively small diameter, a discharge port extending through the head and communicating with the chamber, a check valve for said port, a ring of yielding material surrounding the discharge port and forming a valve seat on the bottom of the cylinder head for the upper end of the sleeve cylinder, and a piston having piston rings fitting in the cylinder and adapted to move the cylinder to and from its seat at the beginning of the respective compression and suction strokes.
24. In a compressor, a cylinder frame, a head for the frame, the cylinder frame having radial ports at its upper end adjacent the head, the head having a substantially flat bottom surface and having a yielding annular seat mounted therein, said head having a discharge port through the central part thereof, a discharge check valve therefor, a sleeve forming a cylinder mounted for limited axial motion in the cylinder frame, the upper end of the cylinder co-operating with the annular seat to form a valve, and a piston having rings engaging the inner surface of the sleeve to shift it by ring friction at the beginning of each stroke of the piston.
25. In a compressor, a cylinder head having a central discharge valve pocket disposed above and joined to the head by a relatively small neck to limit the area of contact of the hot compressed air and conduction of heat therefrom to the cylinder head, there being a central discharge passage leading through the head and neck

into the valve pocket, and a check valve disposed in said pocket and controlling said discharge passage.

26. In a compressor, a cylinder frame having a head, a liner guided at its upper and lower ends in the frame and adapted to be moved into and out of contact with the head by ring friction, and means for moving cooling air in contact with the exterior of the liner between the parts where it is guided in the frame.

27. In a compressor, a hollow cylinder

frame having bearings, a liner in the frame mounted in said bearings, a head on said frame adapted to be engaged by said liner, 15 said liner being movable in said bearings by ring friction, said cylinder frame being spaced from said liner intermediate said bearings, and means for creating air flow along the intermediate part of the liner for 20 cooling said part of the liner.

In witness whereof, I hereunto subscribe my name this 11th day of September, 1924.

BURTON S. AIKMAN.
